(57) **CLAIM**

The ornamental design for a case for electronic communications device, as shown and described.

DESCRIPTION

FIG. 1 is a rear perspective view of a case for electronic communications device showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is an enlarged detail view of the encircled region 8 in FIG. 1.

The dash-dash broken lines throughout the drawing figures depict portions of the case for electronic communications device that form no part of the claimed design. The dash-dash broken lines and unshaded regions bounded by dash-dash broken lines form no part of the claimed design. The dot-dash broken lines in FIGS. 1 and 8 are included for the purpose of delineating the portion included in the enlarged detail view and form no part of the claimed design.
